Bolhofner, both of St. Louis, Mo.

Application January 11, 1939, Serial No. 250,378

3 Claims. (Cl. 91—50)

This invention relates to certain new and useful improvements in a machine adapted, more particularly, for use in applying a liquid re-enforcing agent to the unfinished side of pieces 5 of leather, such as vamps, linings, or the like, in order to stiffen the leather and expedite subsequent operations thereon, especially those involving cutting or die-stamping the leather in producing ornamental designs therein of an 10 open-work nature. The machine is equally well adapted, however, for applying paste, or other liquid substances, to leather.

The application of a re-enforcing agent to leather vamps, or the like, to stiffen the same is 15 commonly practiced in shoe factories, such stiffening of the leather not only rendering the pieces easier to handle and operate on, but enabling the leather to be cut, or die-cut, without leaving ragged edges around the cuts. The 20 stiffening liquid generally employed is quite thin, and the prevailing practice is to apply this liquid to the leather manually by means of a brush, as it has heretofore been considered impossible, or at least impracticable, to apply it successfully in 25 any other fashion. In the larger factories, a relatively large number of operators, usually females, are employed for doing this work alone.

One reason that has made the application of re-enforcing liquid to the leather by hand universal, so far as our knowledge extends, is the 30 fact that the liquid agent employed if not frequently agitated, quickly hardens, assuming the nature of glass. Where the use of machines has been attempted for this purpose, it was found 35 that material left in the container of the machine, or on parts for applying it, for even a relatively short length of time, would harden to such an extent that the machine would have to be taken apart and the hardened material re- 40 moved by a suitable solvent before the machine could again be used. This required the expenditure of considerable time and labor, as no machine suitable for this purpose had ever been devised prior to our invention, so far as we are 45 aware, that could be rapidly disassembled to permit it to be cleaned when necessary. The use of machines for applying the re-enforcing liquid, therefore, has heretofore been considered entirely impracticable, and the brush method, as 50 stated, is universally employed.

Now it is an object of our invention to overcome the obstacles incident to the use of a machine for applying a stiffening agent to pieces of leather, by providing a machine for this purpose of exceedingly simple construction, which

may be readily dis-assembled and reassembled whenever a cleaning operation is necessary.

It is a further object of the invention to provide a machine of this nature which in operation will cause a continuous agitation of the 5 stiffening agent in the container of the machine, and which will permit of the utilization of practically the entire capacity of the container for holding the stiffening liquid.

It is a further object of the invention to provide a machine which may be easily and readily operated, even by an inexperienced person, and which will practically eliminate danger of accident to the hands of the operator from being caught between rollers used in applying the 15 liquid to the leather.

Other objects relate to details of construction of the machine, which may be better understood from the detail description of the invention to follow.

The invention is illustrated in the accompanying drawing, in which—

Figure 1 is an end elevation partly broken away, facing the operator;

Figure 2 is a vertical section on the line 2—2 25 of Figure 1;

Figure 3 is a plan view;

Figure 4 is a rear end elevation, broken away to show a leaf spring support for the pick up roll;

Figure 5 is an enlarged vertical section on the line 5—5 of Figure 3;

Figure 6 is an enlarged vertical section on the line 6—6 of Figure 3;

Figure 7 is an enlarged horizontal section 35 taken on the line 7—7 of Figure 4; and

Figure 8 is a plan view of a vamp showing, by stippling, the re-enforcing liquid applied to one side thereof.

Referring now to the drawing, the numeral 1 indicates the top of a table, or other support, on which our machine is mounted. Said machine comprises a container 2, having side walls 3, end walls 4, and a bottom 5, and being open at the top. Extending along the sides of the machine 45 at the bottom are flanges 6, having apertures to receive screws 7, by means of which the machine is secured on the top of the table.

The numeral 8 indicates a pick-up roll, which is in the form of a hollow metal cylinder having 50 an integral cross-bar, or spoke, 9 near each end providing hubs 10, by means of which the cylinder is mounted on a shaft 11, projecting at its ends beyond the outer ends of the spokes 9. Cast integral with the inner side of each end 55

- wall 4 are two parallel pairs of retaining guide lugs 12, between each pair of which is slidably mounted a plate 13, each plate resting at its lower end on the free end of a leaf spring 14, the other end portion of which is bent to extend between holding pins 15 provided on the inner side of each end wall. Each of the plates 13 is provided with an aperture for receiving the corresponding projecting end of the shaft 11, as clearly shown in Figure 2, so that the pick-up roll is yieldably supported in the container 2, and is normally pressed upward against the under side of a distributing roll 16 by the leaf spring 14.
- 16 The distributing roll 16 is loosely mounted on a drive shaft 17 which is mounted in the bearings 18 provided in the end walls 4. One end of this drive shaft is screw threaded and has a nut 19 applied thereto which, when screwed home, bears against the outer side of the bearing 18 and holds the shaft in position in its bearings. On the opposite end of shaft 17 is a drive pulley 20, and adjacent this pulley is secured a gear 21. At a point on the shaft within the container 2 there is removably mounted in the shaft a stud 23, which engages in a slot 24 provided in the end of the distributing roll 16. The shaft 17 is continuously rotated by the driven pulley 20 and the engagement of stud 23 in the slot 24 causes the distributing roll 16 to be rotated with it. The pulley 20 is driven in the usual manner by a belt (not shown) from any suitable source of power.

Referring to Figures 2 and 7, the end wall 4 of the container adjacent the gear 21 has secured thereon by means of screws 25 two parallel guide members 26, which form a guide way for a slide-bar 27, which is provided intermediate its ends with a slot 28 through which the shaft 17 extends. In the upper end of slide bar 27 there is mounted a bearing 29 for receiving the outer end of a stub shaft 30, on which outer end beyond the slide-bar is mounted a pinion 31, which is adapted to be brought into and out of mesh with the driving gear 21. Secured on the stub shaft 30, as by being press-fitted thereon, is a presser roll 32, which is adapted to be raised or lowered with respect to the distributing roll 16, by means now to be described.

Screw threaded into the lower end of slide-bar 27 is a rod 33, which passes downward through an opening 34 in the top 1 and has an adjusting nut 35 applied to an intermediate screw threaded portion 36, which nut is adapted to bear against the under side of the top 1 to limit the upward movement of the slide-bar 27 and roll 32, which is caused by the pressure of a coil spring 37 surrounding the rod 33 and interposed between the lower end of slide bar 27 and the top of table 1. Secured to the lower end of the rod 33 is a pull rod 38, which at its lower end is connected to a conventional foot treadle (not shown).

When the treadle is depressed the slide bar 27 carrying pinion 31 and presser roll 32 is moved downward; and when pressure on the treadle is released, the coil spring 37 raises these parts to the position shown by dotted lines in Figure 2.

The container 2 is of a size to contain about a gallon of the re-enforcing fluid, the liquid level of which, when the container is filled, being somewhat below the upper edge of the pick-up roll 8, as shown in Figure 1.

A gallon of the re-enforcing fluid is ordinarily sufficient for a day's work. If more of the fluid is required, however, the additional amount may be poured into the container by lifting a cover

plate 39, extending on one side of the distributing roll 16, which is normally held in position on the container by means of fixed, or integral, studs 40 projecting below its underside and being received into holes 41 provided in the upper edge of one of the side walls 3, as indicated in Figure 6.

A second cover plate 42 is located at the opposite side of roll 16, and is provided at its opposite ends and near its outer side with two slots 43, Figure 5, through each of which slots extends a screw 44 which is secured in the upper end of the other side wall 3. This cover plate 42 may thus be adjusted toward or from the upper side of the distributing roll 16, in order to regulate the amount of liquid which will be carried up for application to the leather by said roll.

The bottom of the container is provided with an aperture which is normally closed by a screw plug 45, which is located within an opening 46 provided in the top 1. By removing plug 45, the container 2 may be drained when operation of the machine is to be suspended for a considerable length of time, as at the end of a day's work.

By making the pick-up roll 8 hollow and open at its ends, the liquid in the container will also occupy the greater portion of the interior of the roll, enabling practically the full capacity of the container to be employed for the liquid. Moreover, as the pick-up roll rotates, the liquid on the inside of the roll, as well as that displaced by the exterior of the roll, will be thoroughly agitated and thus kept from hardening so long as the machine is in operation.

The pick-up roll 8 being held in constant contact throughout its length with the under side of the positively-driven distributing roller 16 by means of the leaf springs 14, will be rotated by such frictional contact and will operate to constantly supply the liquid re-enforcing agent to the surface of said distributing roll.

Normally, the presser roll 32 is in the elevated position indicated by the dotted lines in Figure 2. If a vamp, such as shown by Figure 8, and indicated by the numeral 47, is to be treated, the operator places said vamp with its unfinished side downward on the top 1 and moves it into engagement with the top of distributing roll 16 and at the same time presses the foot treadle downward, thereby bringing the pinion 31 into mesh with gear 21 and the presser roll 32 into engagement with the upper, or finished side of the vamp. The vamp then rapidly passes between the two rolls 16 and 32 and its under side is pressed by roll 32 into firm engagement with the upper side of the distributing roll 16, so that the reenforcing liquid is evenly distributed over the under, or unfinished side, of the vamp as indicated by the stippled portion 48 of Figure 8. The passage of the vamp 47 between the rollers is indicated by the dotted lines in Figure 1. Just as the rear portion of the vamp is about to pass between the rollers, the operator releases pressure on the foot treadle, and spring 37 immediately causes the roller 32 to be raised, thus preventing the roll 32 from coming in contact with roll 16 and having its surface covered with the liquid.

Should fingers of the operator be caught between the rolls 16 and 32, the upward pressure of the foot treadle on the foot of the operator occasioned thereby will immediately cause her to release pressure on the foot treadle and allow the roll 32 to be raised. Ordinarily, however, the operator would promptly release pressure on the foot treadle the moment her fingers

became engaged. As the pressure exerted by the upper roll 16 is only that produced by the operator, there is practically no danger whatever of sufficient pressure being exerted to injure the 5 fingers, as the operator would instinctively release pressure of the foot treadle the moment her fingers came in contact with the rolls.

When it becomes necessary to disassemble the machine for the purpose of cleaning it, or for 10 any other purpose, the nut 19 is first removed, the shaft 17 pulled out far enough to carry the stud 23 out of the slot 24, when the stud is pulled out of the shaft by means of pliers and the shaft with its gear 21 and pulley 28 pulled 15 entirely out of the machine. This of course enables roll 16, to be removed. The pull rod 38 is then lifted out of engagement with the rod 33, and the latter unscrewed from engagement with the slide bar 27, which permits the latter 20 with its pinion 31 and roller 32 to be lifted off of the machine. The pick-up roll 8 may now be removed by simply lifting it out of the machine, the plates 13 sliding out of engagement 25 with the lugs 12. These operations require only a few minutes, and the machine may be reassembled in the same short length of time.

We claim:

1. In a machine of the class described, a container, a leaf spring and guide members provided 30 on the inner side of each end wall of said container, an apertured plate slidably mounted in each set of said guide members and supported on one of said leaf springs, a pick-up roll having a shaft mounted in the apertures of said 35 plates, a distributing roll mounted in said container having driving means and a driving gear, and frictionally engaging the upper side of said pick-up roll against the resistance of said leaf springs, a presser roll located above said distributing roll and having a pinion, means for 40 manually lowering said presser roll to bring its pinion into engagement with the gear of the distributing roll, and automatic means for raising said presser roll when released from manual 45 control.

2. In a machine of the class described, a container, guide members provided on the inner side of each end wall of said container, a plu-

rality of spaced pins fixedly mounted on and projecting inward from each of said end walls, a leaf spring threaded between said pins on each end wall and having a free end extending beneath said guide members, an apertured plate 5 slidably mounted in each set of guide members and supported on the free end of the leaf spring beneath said members, a pick-up roll having a shaft mounted at its ends in the apertures of said plates, a distributing roll mounted in said container having driving means and a driving gear, and frictionally engaging the upper side of said pick-up roll against the resistance of said leaf springs, a presser roll located above said 10 distributing roll and having a pinion, means for manually lowering said presser roll to bring its pinion into engagement with the gear of the distributing roll, and automatic means for raising said presser roll when released from manual 15 control.

3. In a machine of the class described, in combination with a container having a pick-up roll 20 removably mounted therein, a shaft slidably mounted in the walls of the container and having a securing nut applied to one end thereof, a distributing roll loosely mounted on said shaft 25 and having at one end a slot, a removable pin carried by said shaft and engaging in said slot, a slide-bar mounted on one end of said container and having a slot receiving said shaft, a stub 30 shaft mounted at one end in a bearing on said slide bar and having a presser roll secured thereon located above said distributing roll, a pulley and a gear on the shaft of the distributing roll, a pinion on the shaft of said presser roll, a 35 spring normally holding said slide-bar and its shaft, pinion and presser roll in a raised position, a rod removably secured in the lower end of said slide-bar, means for lowering said slide bar at the will of the operator detachably 40 connected to said rod, and a stop on said rod for limiting the upward movement of said slide-bar, the combination being such that by unscrewing the nut from said shaft, removing the pin therefrom and removing said rod from the slide-bar, 45 the entire machine may be disassembled.

PETER BOLHOFNER.
THEODORE KOCH.
